UNITED STATES PATENT OFFICE.

THOMAS F. WILLIAMS, DONALD W. COY, AND HARRY B. PRUDEN, OF CHICAGO, ILLINOIS, ASSIGNEES TO POWDERED COAL ENGINEERING AND EQUIPMENT COMPANY, OF CHICAGO, ILLINOIS, A CORPORATION OF DELAWARE.

APPARATUS FOR CARBURETING AIR WITH SOLID FUEL.

1,385,412.

Specification of Letters Patent. Patented July 26, 1921.

Application filed August 26, 1918. Serial No. 251,581.

To all whom it may concern:

Be it known that we, THOMAS F. WILLIAMS, a subject of Great Britain, DONALD W. COY and HARRY B. PRUDEN, citizens of the United States, all residing in Chicago, county of Cook, and State of Illinois, have invented certain new and useful Improvements in Apparatus for Carbureting Air with Solid Fuel, of which the following is

10 a specification.

Our invention relates more specifically to the art of mixing finely divided fuel with air for the purpose of combustion in furnaces, etc. For this purpose it is necessary 15 to supply a continuous supply of air and powdered fuel which are mixed as near as may be in fixed proportions and fed to a burner. In the form of apparatus to which our invention is more particularly intended 20 to be applied, powdered fuel is fed by means of a conveyer to a mixing apparatus. It is the purpose of this invention to provide means whereby the powdered fuel may be shipped and received at the point of consumption in receptacles or containers, and the latter conveniently and quickly connected to the chute of the conveying mechanism will have a substantially continuous supply of fuel. With this in view we employ 25 containers of uniform character in which the powdered fuel is packed for shipment to the point where it is to be used, and provide a small number of connecting funnels one of which is connected with each 30 container preparatory to discharging the contents of the latter, and serve as a means for connecting it to the chute of the fuel mixing machine. The nature of the invention will appear from the drawings and the following description in which we have set forth in detail a preferred embodiment of our invention. It is to be understood, however, that the specific disclosure is for the 35 purpose of exemplification only, and that the scope of the invention is defined in the following claims in which we have endeavored to distinguish it from the prior art without however, relinquishing or abandoning any portion or feature thereof.

40 In the accompanying drawings forming a part of this application, Figure 1 is a side elevation of a preferred form of the inven-

tion, parts, however, being broken away and shown in section; Fig. 2 a perspective of the upper end of the chute of the machine, and 55 the lower end of the funnel about to be attached thereto; Fig. 3 a section upon the line 3—3 of Fig. 1 on an enlarged scale; and Fig. 4 a section of the same detail and on the same plane of section as Fig. 1 but on an enlarged scale.

Each part is identified by the same reference character wherever it occurs in the several views.

Referring first to Fig. 1, the chute of the 60 machine is indicated at 5 as attached at 6 to the casing of the carbureter and communicating with the fuel chamber 7 through the bottom of which the screw conveyer 8 extends. As this specific mechanism forms no 70 part of the present invention, it is not necessary to describe the coal conveying means further. The chute 5 is shown as a casting, the upper end or mouth of which is thickened or flanged as at 9, and receives a ring 75 or annulus 10, which is riveted or otherwise secured thereto. The annulus 10 is formed with an inner flange 11, which sits in a rabbet 12, formed in the upper end of the casting and is provided with any suitable number 80 of bayonet joint slots 13, here shown as four in number, said slots being located in the inner face of the annulus to receive corresponding pins 14, projecting outwardly 85 from a flange 15, upon the funnel or intermediate member 16, by which the container 17 is attached to the chute.

The funnel 16 is formed of sheet metal, and riveted to a casting 18 which forms a coupling member and also a housing for 90 certain mechanism which will be presently described. Upon the casting is formed a cylindrical flange or apron 15, referred to above, which when the funnel or intermediate member is in position on the mouth of 95 the chute, fits within the annulus 11 at the top of the chute. In applying the flange member to the chute, the pins 14, are brought into registry with the vertical arms 19, of the respective bayonet slots, whereupon the flange and casting drop until the flange rests upon the seat 20, in the upper end of said chute, see Fig. 1. This brings 100 the pins to the bottoms of the vertical mem-

bers of the respective bayonet slots, and into registry with the horizontal members 21 of said slots. By a slight rotation of the funnel member, the pins are carried into the 5 horizontal members of the respective bayonet slots, and the structures thus firmly united.

As heretofore stated the container 17, employed in connection with our invention, are 10 of uniform construction, at least in so far as the outlets thereof are concerned, and adapted to have the flange members readily attached thereto. Preferably the containers are metallic barrels, as shown in Fig. 1 of 15 the drawings, in which the lip is provided with an external bead 22, which is utilized for the purpose of securing the funnel thereto. For this purpose the upper edge of each of the funnels is provided with a cast 20 annulus 23, of such internal diameter as to receive the bead 22 therein, and said annulus is provided with a suitable number of thumb screws 24, the upper ends of which are adapted, when screwed inward, to take over 25 said bead, and so lock the barrel to the annulus, all as fully shown in Fig. 1. The upper edge of the sheet metal funnel 16, is flanged outwardly at 25, and is secured to annulus 23 by means of a ring 26 and bolts 30 or rivets 27. The funnel is attached to and detached from the barrels by manipulating the screws in an obvious manner.

When a barrel is to be mounted upon the carbureting apparatus to discharge its supply of powdered fuel, the head of the barrel is removed or opened and the funnel attached thereto. In order to prevent spilling or discharging part of the fuel when the barrel is being put in position, we provide 35 the casting to which the lower end of the funnel is attached with a closure which remains closed until the funnel and barrel are in position on the apparatus. For this purpose the casting 28 is provided with a pair 40 of doors or shutters 29, 30, which are pivoted at the diameter of the casting upon a pivot rod 31, and seat against an internal flange 32 upon said casting. Before the funnel is applied to the carbureting apparatus, the shutters are closed or held in closed 45 position by the latches 33, 34, respectively, said latches being forced into holding position by the springs 35, 36, engaging the latches at one end and received in the housing 37, 38 at the other end. The latches are pivoted at 39, 40 respectively to the housing. Obviously in order to close the shutters it is merely necessary to press them into closed 50 position, the latches yielding for this purpose under the camming action until they are passed. In order to automatically release these gates or shutters, the casting is formed with vertical bores 41, 42, which receive headed pins 43, 44 the heads of which, 55 when the bolts are thrust upward engaging

the lower edges of the respective latches at 45, 46. The lower ends of the pins, speaking with reference to the position in Fig. 1, project through the horizontal flange 47, of the casting which when the funnel is applied to 70 the chute of the carburetor, rests upon upper face 48 of the mouth of the chute. The upper face 48 is provided with cam slots or recesses 49, which are so arranged that when the pins 44 register with the vertical limbs 75 of the bayonet slots, the vertical sliding pins 41, 42 are in register with the deepest portions of the respective cam slots. Thus, when the funnel is first applied to the chute the pins 41, 42 are not disturbed. When 80 however, the funnel is rotated to shift the pins 44 into the horizontal limbs of the respective bayonet slots, the sliding pins 41, 42 move along the cam slots and are forced upward thereby into contact with the latches 85 33, 34 respectively, to release the same from the gates. The latter then drop by gravity, and the pressure of the finely divided material above them, and the coal in the container is then free to flow into the carbureting device. Thus by the very movement of securing the parts together, communication between the funnel and barrel on one hand and the apparatus on the other is established. The casting is also formed with an outer 90 flange 50, which overlaps annulus 10 on the outside, and with hand holes and cover plates 51, 52 to provide access to the latches. 95

In a construction of the character just described, it is desirable that precaution be 100 made for warning the operator in charge of the plant whenever the barrel or other container is empty so that a new container may be substituted therefor. With this object in view, we provide a means for operating an 105 alarm which comprises a movable member with a motor which constantly tends to move the same, and which when moved gives an indication to the operator but which is held against movement until the container is 110 empty by the charge of the latter. Preferably the alarm is mounted on the upper end of the chute, and in the specific construction shown, the casting 5 forming the upper end 115 of the chute is formed or provided with an opening 52 which is covered by the housing 53, containing the motor of the alarm. Preferably a rotary motor is employed, and in this instance we have illustrated a pneumatic motor comprising a wheel 54 mounted 120 in said housing 53, and normally under pressure of air through an inlet 55 which may be connected with a source of air pressure such as that which supplies the air for mixing with the fuel. 56 represents an exhaust 125 conduit which may open to the air if desired. The housing 53 is formed with the lateral tubular extension 54, which is provided with bearings 55, 56 for the shaft 57 of the motor. When the housing is in position on the cast- 130

ing 5, the sleeve or tubular extension 54 projects into the path of the fuel within the chute, and shaft is provided beyond the sleeve with a pair of paddles 58. The housing is closed by a cover plate 59.

The wheel or motor 54 being constantly under pressure of air will tend to turn the shaft 57, but the pressure is not sufficient to turn the same against the resistance of the powdered fuel in which the paddle 58 is immersed until the contents of the container have been exhausted. The shaft is adapted when rotated to operate any kind of an alarm, but in the specific construction shown it is arranged to close an electric circuit which may contain a bell, lamp, or other indicating device. A plug 60 of insulating material extends through the axial opening 61 in the cover plate 59 and into the axial chamber 62 of the motor wheel. A contact post 63 extends through the insulating plug and is formed with a lateral arm 64 which extends beyond the insulating plug into chamber 62. The post 63 is connected at one end into a circuit alarm by means of the set nuts 65 in the usual manner. Within the chamber 62 is carried a metallic ball or roller 66, which, when the wheel is at rest occupies the lowermost position shown in dotted lines 66^a. The other end of the circuit is grounded on the machine, and when the wheel revolves the ball or roller 66 is carried up to the position shown in full lines in which it completes a circuit between the wheel and the contact post 63 operating the bell or other indicating device.

The operation of the invention will be readily understood from the foregoing description. When a fresh supply of powdered fuel is needed, a barrel is opened and a connecting funnel with its gates closed is attached thereto by fitting it over the chime and turning the screws thereof under the bead. The barrel with the funnel attached thereto is then placed in inverted position on the supply chute of the mixing apparatus and turned until the pins projecting from the coupling casting on the funnel register with the upper ends of the bayonet slots on the chute. The barrel is then given a turn to bring said pins into the horizontal members of the respective bayonet slots or grooves to lock the funnel securely to the chute. The application of the funnel to the chute brings the latch operating pins in register with the deeper portion of the cam grooves in the upper face of the chute annulus. As the barrel is given the slight rotation described to lock it to the chute, the pins ride up the incline ends of the respective slots and engage the latches to withdraw them from beneath the respective gates. The latter will drop under the weight of the fuel which fills the chute re-

ceiving chamber of the mixing apparatus. The powdered coal in the chute closely surrounds the paddles of the alarm, preventing the rotation of the shaft and motor wheel and the circuit closing ball comes to rest in its lowermost position in which the electric alarm circuit is open. As the supply of coal approaches exhaustion, it uncovers the paddles of the alarm permitting the shaft and wheel to rotate under the impulse of the blast of air, and the ball is again carried up to the circuit closing position operating the bell or other alarm. The attendant then prepares to substitute a full barrel for the empty barrel by opening the former and applying the funnel thereto.

We claim:

1. In a device of the class described and in combination with the feeding means thereof, a chute delivering to said feeding means a funnel having means for attachment to a package to be emptied into said chute, means for closing said funnel, and means for removably attaching the funnel to the chute. 90

2. In a device of the class described and in combination with the feeding means thereof, a chute connected to said feeding means, a funnel adapted to be removably secured to the chute, means on the funnel for securing a package thereto, and means for closing the funnel, adapted to be released by the attachment thereof to the chute. 95

3. In a device of the class described and in combination with the feeding means thereof, a chute connected to said feeding means, a funnel adapted to be connected to the chute, a closure for the funnel, a latch for maintaining the closure in the closed position adapted to be released by the application of the funnel to the chute, and means on the funnel for engaging a package of powdered material. 100

4. In a device of the class described and in combination with the feeding means thereof, a chute, a funnel adapted to be secured to the chute, by a rotative movement relative thereto, cam surfaces on said chute, gates in the funnel, latches for maintaining said gates closed, means operated by said cam surfaces for releasing the latches. 110

5. In a device of the class described and in combination with the feeding means thereof, a chute connected to said feeding means, a funnel adapted to be secured to the chute by a rotative movement relative thereto, cam surfaces on said chute, gates in the funnel, pivoted latches for maintaining said gates closed, and pins adapted to be engaged by the cam surfaces to lock the latches 120 when the funnel is rotated.

6. In a device of the class described and in combination with the feeding means and chute thereof, bayonet joint slots at the entrance end of said chute, a funnel having 130

pins on its lower end adapted to enter said bayonet slots and to be secured therein by a partial rotation of the funnel, swinging gates in the funnel, pivoted slots for maintaining said gates closed, vertically movable pins engaging the slots for swinging the same out of engaging position, and cams on the chute engaging the respective pins to move the latter and operate the respective latches when the funnel is given a partial 10 rotation to secure it to the chute.
